(57) **CLAIM**

The ornamental design for the touch-screen interactive multimedia display, as shown and described.

DESCRIPTION

FIG. 1 is a front elevational view of a first embodiment of our touch-screen interactive multi-media display, showing our new design, with the touch screen indicia removed for illustrative purposes only. The electronic gaming device, pair of speaker grills and a player-card slot are shown in dashed lines, and are not part of the claimed design; FIG. 2 is an enlarged partial view of the display of FIG. 1 depicting the touch screen; FIG. 3 is a bottom plan view of the view of FIG. 2; FIG. 4 is a right side, elevational view of the view of FIG. 2, the left side being substantially a mirror image thereof; FIG. 5 is a front elevational view of a second embodiment of our display, showing our new design, with the touch screen indicia removed for illustrative purposes only. The electronic gaming device, pair of speaker grills and a player-card slot are shown in dashed lines, and are not part of the claimed design;

FIG. 6 is a right side, elevational view of the view of FIG. 5, the left side being substantially a mirror image thereof; FIG. 7 is a top plan view taken along lines 7—7 in FIG. 6; FIG. 8 is bottom plan view taken along lines 8—8 in FIG. 6; and,

FIG. 9 is an enlarged partial view of the Interface of FIG. 5 depicting the touch screen.
